COIN-CONTROLLED LOCK

Thomas F. Curren, Altadena, Calif., assignor to
 Pacific Coin Lock Co., Los Angeles, Calif., a
 corporation of California

Application November 13, 1945, Serial No. 627,981

15 Claims. (Cl. 194—59)

1

This invention relates generally to coin control locks of the type commonly installed on public pay stations, and relates more particularly to improvements in the coin releasing latch which controls the manual bolt retracting operator.

Coin control locks now in general use, fail to cope with all conditions and situations under which the locks are required to operate. The locks of this type operating in public service are subjected to tampering and abnormal usage and require a lock that will not only stand abuse, but the various devices that may be attempted to render the control inoperative or permit free use of the station. Prior coin control locks have failed to assure the expectant user admittance after he has trustingly inserted a coin. For example, many ordinary coin control locks depend upon the return of the keeper-engaging bolt to its normal position for reception of a coin. If for any reason the bolt fails to return to normal position, as when a previous user has tampered with the keeper, e. g. by filling it with paper, such locks are found either to be made inoperative, or uncontrollable as intended.

A general feature of the invention is to provide a coin control lock that will obviate the existing defects of prior locks and be capable of operating under adverse treatment and abnormal conditions. The lock is of sturdy construction and designed for unfailing operation, thus assuring the user admittance upon the insertion of the proper coin.

The invention contemplates particularly a novel coin releasing latch for controlling the operation of the outside operator, and in this connection, a control which is independent of the bolt to the extent that the position of the bolt does not affect the operation of the coin releasing latch.

Thus the coin releasing means is associated with, but operates independently of the bolt, allowing free operation of the bolt from its extended position to its fully retracted position. Because of its independence from the bolt position, the coin releasing means is assured of being conditioned to fully retract the bolt upon insertion of the proper coin, even though the bolt may only be partially projected. Therefore the lock cannot become inoperative, and the coin releasing latch is in condition for reception of a coin after each opening and closing of the door.

Other features and objects of the invention will be better understood from the following detailed description, throughout which reference is had to the accompanying drawings, in which:

Fig. 1 is a vertical cross-sectional view taken substantially as indicated by line 1—1 of Fig. 2;

Fig. 2 is a vertical transverse sectional view taken on line 2—2 of Fig. 1;

2

Fig. 3 is a horizontal transverse sectional view taken on line 3—3 of Fig. 1;

Fig. 4 is a fragmentary vertical sectional view taken on line 4—4 of Fig. 2, illustrating the parts in their normal unactuated position with a coin in position to release the latch upon movement of the outside operator;

Fig. 5 is a view similar to Fig. 4 illustrating the position of the parts after the outside operator has been actuated and the bolt fully retracted;

Fig. 6 is a view similar to Fig. 5 illustrating the position of the parts after release of the outside manual operator;

Fig. 7 is a fragmentary vertical transverse section taken on line 7—7 of Fig. 1;

Fig. 8 is a fragmentary vertical sectional view taken on line 8—8 of Fig. 7;

Fig. 9 is a perspective view of the bolt embodied in the invention;

Fig. 10 is a perspective view of one of the latches embodied in the invention;

Fig. 11 is a perspective view of the control plate associated with the latch means embodied in the invention; and

Fig. 12 is a perspective view of the coin releasing latch plate or connecting member between the outside manual operator and the bolt.

The coin control lock illustrated in the drawings includes generally a lock body 10 attached to the door D and carrying a sliding bolt 11. A keeper 12 is located adjacent the door opening and adapted to receive the bolt for locking the door. Manual operating means 13, termed the outside operator, is provided at the outside of the door for retracting the bolt 11 to open the door.

30 A coin releasing latch assembly 14 is provided between the outside operator 13 and the bolt 11 for holding the outside operator inoperative until the proper coin has been inserted. The latch assembly 14 includes a control latch 141 associated with and operable independently of the bolt, and a secondary latch 15. During the later described operating sequence, the latch means 141 is momentarily held inoperative by the secondary latch 15 which is associated with and conditioned by operation of the latch 141. The secondary latch 15 allows the outside operator 13 to be repeatedly operated during opening of the door, rendering the coin releasing latch 141 inoperative, until the bolt has been retracted as by closing of the door.

40 An inside manual operator 16 located at the inside of the door, retracts the bolt independently of the outside operator so that it is at all times conditioned for operation.

45 The body 10 of the lock includes a plate-like member attached to the outside of the door D by suitable screws 17 and forms a mounting for the various parts of the lock. Typically, the bolt 11

50

is substantially square in transverse cross-section and is slidably carried on the outer face of the body between projections or guides 18. The wedge shaped outer end or keeper-engaging portion 19 normally projects from the side of the lock. A retaining plate 29 secured to the guides 18 by screws 21 retains the bolt in the guideway. The bolt is yieldingly urged in its extended or projected position by spring 22 connected to a projection or arm 23 on the rear end of the bolt and a projection 24 on the retaining plate 20.

The latch 141 includes a control plate 25 slideable on the outer faces of the guides 18 and at the inside of a retaining plate 26, see Figs. 3, 4 and 12. The plate 26 is secured at its bifurcated forward end 261 to the outer face of the guides 18 by screws 26a and has a lateral offset portion 26b spaced from the plate 25 to allow reception of a coin C, as illustrated in Figs. 3 and 4 of the drawings. The rear end of the plate 26 is secured to and in spaced relation with the outer faces of the guides 18 by screws 25c. The retaining plate 26 is provided with an elongated slot 26d adjacent the rear end of the plate, to pass arm 23 on the bolt 11. A second slot 26e in the plate 26, located under the slot 26d adjacent the lower edge of the plate, receives a spring safety catch 75 as will be later described.

As will appear, under the influence of the outside operator 13, the plate 25 is capable of limited reciprocations relative to the bolt, followed by engagement with the bolt to retract it from the keeper. Plate 25 has a lateral projection or finger 28 engageable with a shoulder 29 formed on the bolt 11 at the end of a recess 30 in the outer face of the bolt 11. A notch 31 in the upper edge of the plate 25 is adapted to receive the active end of a pivoted pawl 32 for preventing reciprocation of the plate previous to the insertion of a coin. The pawl 32 is pivotally carried on one of the screws 26c in the upper portion of the space S, and is urged downwardly into engagement with the plate 25 by a spring 34. Downwardly projecting spaced lugs 35 are provided at the under side of the plate 25 to receive a pin 36 carried on an arm 37 fixed to stem 38 of the outside operation 13. Construction and movement of the operator 13 to cause reciprocation of the control plate 25, will be later more fully described.

Releasable coin retaining means 39, see Fig. 4, is provided in connection with the control plate 25 to retain a coin C. The means 39 momentarily holds and permits the coin to release the pawl 32, and in turn allows reciprocation of the control plate 25. The coin retaining means 39 includes a pin 40 projecting from the outer face of the plate 25 adjacent its lower edge. A spring-urged latch plate 41, see Figs. 3 and 11, located behind the control plate 25 has projections 42 and 43 extending through elongated openings 44 and 45 in the control plate. The latch plate has limited relative movement with respect to the plate 25 and has movement therewith. The coin C inserted in the usual coin slot 78 drops through the chute 71 into the space S between the control plate 25 and the retaining plate 26, coming to rest between the pin 40 on the control plate 25 and the rearward projection 42 on the latch plate 41. The latter is positioned behind the control plate 25 and is received within the bolt recess 30. Rotation of the outer operator 13 causes reciprocation of the control plate 25 in a rearward direction, bringing finger 28 on the plate 25 into engagement with the bolt shoulder 29. The coin retained between pin 40 and projection 42 engages

pawl 32, causing pivoting of the pawl out of the notch 31 in the control plate 25, thus allowing retraction of the bolt 11.

The secondary latch means 15 includes a pawl 46 pivotally carried in a slot 47 in the upper guideway 18. The outer end of the pawl 46 is urged downwardly by a spring 48 to normally rest on the upper face of the latch control plate 41 and overlie a portion of bolt 11, as clearly illustrated in Figs. 7 and 8. Plate 41 being of substantially the same height as the bolt 11, is confined vertically between guides 18, and laterally between the inner face of the control plate 25 and the outer face of the bolt recess 30.

A spring 48 attached to the forward projection 43 on plate 41 and to a forwardly projecting arm 49 on the control plate 25, yieldingly urges the latch plate 41 forwardly. The outer end of the projection 42, the spring 48, and the arm 49 are received in the bifurcated end of the plate 26 for relative movement. The upper ends of the bolt 11 and the latch plate 41 are in substantially the same plane. The bolt 11 is provided with a camming notch 50 in its upper face and the latch plate 41 is provided with a forwardly facing shouldered notch 51 in its upward face. Notches 50 and 51 are adapted to receive the active end of the pawl 46 upon actuation of the control plate 25. The notch 50 and the notch 51 are normally in staggered relation, as clearly illustrated in Figs. 4 and 8.

When the coin releasing latch means 141 is in its normal position, movement of the control plate 25 by the outside operator 13 causes simultaneous movement of the latch plate 41 through the association of projection 43 with the receiving slot 45. The finger 28 on the control plate 25 is normally in spaced relation to the bolt shoulder 29, thus allowing slack motion between the control plate 25 and the bolt 11. This slack motion allows the staggered notches 50 and 51 in the bolt 11 and the latch plate 41, respectively, to come into alignment simultaneously with the engagement of the finger 28 with shoulder 29. At this time the coin has cammed the pawl 32 out of the notch 31 in the plate 25. Further movement of the control plate 25 retracts the bolt 11.

Upon release of the outside operator 13, a spring 52 connected with the arm 37 and a projection 53 on the lock body, yieldingly urges the arm 37 and control plate 25 forwardly. The engagement of the finger 28 with the shoulder 29, as described above, remains, under normal conditions, until the bolt 11 reaches its fully extended position and the notches 50 and 51 remain in alignment. Thereafter the control plate 25 starts to move relative to the bolt 11 and the pawl 46 is received in the notches 50 and 51. Relative movement between the plate 25 and the bolt 11 brings the shouldered notch 51 into engagement with the pawl 46, stopping further movement of latch plate 41. The control plate 25 continues to move relative to the bolt 11 and the latch plate 41 until the projection 42 on the plate 41 engages the rear end wall of the slot 44. The relative movement between the latch plate 41 and the control plate 25 opens up the space between the pin 40 on the plate 25 and the projection 42 on the plate 41, thus releasing the coin C. The coin drops into the lower portion of the housing H, encasing the lock proper. The pawl 46 cooperating with the notch 51 in the latch plate 41, and the projection 42 on the outer face of the latch plate 41 cooperating with the rearward end wall of the opening 44, prevent return of the control plate 25 to its normal coin

receiving position. With the parts in this condition, the pawl 32 is prevented from engaging the notch 31 and the manual means is conditioned for repeated operation for retraction of the bolt 11.

The bolt 11, when retracted from the keeper 12 allows the door to be opened. During the bolt retracting movement, the pawl 46 engages the notch 51, preventing the full return of the control plate 25. Upon closing of the door D, the projecting portion 19 of the bolt 11 engages the keeper 12 causing relative retraction of the bolt with respect to the plate 25 and its latch control plate 41. This retraction brings the forward end of the camming notch 50 into engagement with the under side of the pawl 46, camming the pawl from the notch 51 in the latch plate 41, and the spring 52 operating through the arm 37, pin 36 and projections 35, returns the plate 25 and its latch control plate 41 to their normal position. This reconditions the coin releasing means 14 for reception of a second coin.

Manual operating means or operator 13 is located at the outside of the door D and its stem 38 is rotatable on the lock body 10 below the bolt 11. The stem 38 is rotatably carried in opening 80 in the body 10 and a bearing bracket 81 secured to the body by screws 82. The arm 37 of the stem 38 is positioned in the space between the inner side of the bracket and the body 10.

Manual operating means 16 located at the inside of the door includes generally an operator 60 rotatably carried in a bearing boss 61 at the inside of the lock body 10. The inner end of the operator 60 carries a fixed double cam 62 operable to cause retraction of the bolt 11 by rotation of the operator in either direction, see Fig. 8.

The operative connection between the cam 62 and the bolt 11 includes pivoted lever 63 carried on the lock body and pivoted on the stem 38 of the outside operator 13. The lever 63 and the cam 62 are received in a recess 65 in the back side of the bolt 11, see Fig. 3. The end wall 66 of the recess 65 is engageable by the rear edge of the lever 63 to transmit movement of the lever to the bolt. A second pivoted lever 67, acting as a shoe between the cam and the lever 63, is pivotally carried by a pin 68 secured to the body 10. A spring 69 returns the operating means 16 to its normal position.

Rotation of the operator 16 causes rotation of the cam 62 and lever 63 through the shoe 67, and bringing of the lever into engagement with the shoulder 66 to retract the bolt 11. It is apparent that the inside operator 16 is capable of actuation at all times to retract the bolt and regardless of the condition of the remaining parts of the latch assembly.

Assuming the parts are in their positions illustrated in Figs. 1, 2, 3, 4, 7 and 8, and the proper coin has been inserted, the lock is in condition for retraction of the bolt. Rotation of the outside operator 13 causes reciprocation or inward travel of the control plate 25 through the pin 36 engaging lug 35 on plate 25. The coin received between the projection 40 on the plate 25 and the projection 42 on the latch plate 41, shown in Fig. 4, is in position to engage pawl 32. The engagement of the coin with the pawl 32 cams the pawl out of the notch 31 in the control plate, allowing further inward travel of the plate 25. Initial inward travel of the plate relative to the bolt brings notches 50 and 51 into alignment at the time the finger 28 engages shoulder 29 on

the bolt 11. After finger 28 engages shoulder 29, further inward movement of the plate 25 retracts the bolt 11 and moves the notches 50 and 51 to positions just beyond the end of the pawl 46 where the pawl is released, see Fig. 5.

Upon release of the outside operator 13 after opening of the door, the spring 52 connected with the arm 37 urges the plate 25 forward or outward toward its normal position. If for any reason the bolt does not return, the pawl 46 will be held released by the bolt and the plate 25 will move relative to the bolt and thus cause the notches 51 to move out of alignment with the notch 50 in the bolt, preventing engagement of the secondary latch means 15. The secondary latch means as described above, when in operation causes release of the coin, but due to the failure of the bolt to return, the notch 50 in the bolt is held out of register with the pawl 46, thus preventing engagement of the pawl with the notch 51. The coin retained in the control latch 14 allows a repeated retraction of the bolt to assure entrance into the pay station.

Upon opening of the door after one or more operations of the outside operator, the operator is released allowing a full unhampered extension of the bolt. Upon the latch plate reaching a position where its finger 28 disengages shoulder 29, the notches 50 and 51 are in alignment and engageable by the pawl 46, thus preventing further outward movement of the plate 41 and permitting relative movement of the plate 25. This relative movement between the plate 41 and plate 25 results in opening of the space between the pin 40 and the projection 42 allowing release of the coin. The plate 41 holds the control plate 25 from returning to its fully outward or normal position, by projection 42 engaging the wall of the opening 44 in the plate 25, until the door has been closed. Closing of the door causes the end 19 of the bolt 11 to engage the keeper 12. Engagement of the bolt with the keeper 12 produces full retraction of the bolt. This retraction of the bolt brings the forward end of the notch 50 into camming engagement with the under side of the pawl 46 disengaging it from the notch 51, allowing the return of the plate 25 and its latch plate 41 to their normal positions.

I claim:

1. A coin controlled lock including mechanism comprising a retractable keeper engaging bolt and movable operating means therefor, said mechanism being movable in bolt retracting direction, a latch element normally allowing limited but preventing complete bolt retracting movement of said operating means and displaceable to a released position, means conditioned by reception of a coin to transmit movement between said mechanism and the latch element for releasing the element in response to bolt retracting movement of the mechanism, and a holding part acting independently of the coin after release of the latch element to prevent relatching thereof to thereby permit repeated retraction of the bolt by said operating means.

2. A coin controlled lock including mechanism comprising a retractable keeper engaging bolt and movable operating means therefor, said mechanism being movable in bolt retracting direction, a latch element normally allowing limited but preventing complete bolt retracting movement of said operating means and displaceable to released position, means conditioned by reception of a coin to transmit movement between said mechanism and the latch element for

releasing the element in response to bolt retracting movement of the mechanism, a holding part acting independently of the coin after release of the latch element to prevent relatching thereof to thereby permit repeated retraction of the bolt by said operating means, and means operable in response to retraction of the bolt independently of said operating means to release the holding part and permit relatching of the latch element.

3. A coin controlled lock including mechanism comprising a retractable keeper engaging bolt and movable operating means therefor, said mechanism being movable in bolt retracting direction, a latch element normally allowing limited but preventing complete bolt retracting movement of said operating means and displaceable to released position, means for receiving and supporting a coin in a position to transmit movement between said mechanism and the latch element to release the element in response to bolt retracting movement of the mechanism, and a holding part acting independently of the coin after release of the latch element to prevent relatching thereof to thereby permit repeated retraction of the bolt by said operating means.

4. A coin controlled lock including mechanism comprising a retractable keeper engaging bolt and movable operating means therefor, said mechanism being movable in bolt retracting direction, a latch element normally allowing limited but preventing complete bolt retracting movement of said operating means and displaceable to released position, means for receiving and supporting a coin in a position to transmit movement between said mechanism and the latch element to release the element in response to bolt retracting movement of the mechanism, a holding part acting independently of the coin after release of the latch element to prevent relatching thereof to thereby permit repeated retraction of the bolt by said operating means, and means operable in response to retraction of the bolt independently of said operating means to release the holding part and permit relatching of the latch element.

5. A coin controlled lock comprising a bolt movable between a keeper engaging position and a retracted position, movable operating means for displacing the bolt to said retracted position, a releasable latch element normally allowing limited but preventing complete bolt retracting movement of said operating means and displaceable to a released position, means for receiving and supporting a coin in a position to transmit movement between said operating means and said latch element to release the element in response to movement of the operating means in a bolt retracting direction, a holding part acting independently of the coin after release of the latch element to prevent relatching thereof and permit repeated retraction of the bolt by said operating means, and means operable in response to retraction of the bolt independently of said operating means to release the holding part and permit relatching of the latch element.

6. A coin controlled lock including mechanism comprising a retractable keeper engaging bolt and movable operating means therefor, said mechanism being movable to retract the bolt, a latch element normally allowing limited but preventing complete bolt retracting movement of said operating means and displaceable to a released position, means for receiving and supporting a coin in a position to transmit movement between said mechanism and said latch element

to release the element in response to bolt retracting movement of the mechanism, and a holding part acting to prevent complete return of said mechanism to normal after movement in a bolt retracting direction to thereby prevent relatching of said latch element and permit repeated retraction of the bolt by said operating means.

5 7. A coin controlled lock comprising a bolt movable between a normal keeper engaging position and a retracted position, operating means movable between a normal condition and an actuated condition to retract said bolt, a latch element normally allowing limited but preventing complete bolt retracting movement of said operating means from said normal condition and displaceable to a released position, means for receiving and supporting a coin in a position to transmit movement between said operating means and said latch element to release the element in response to movement of the operating means in a bolt retracting direction, a holding part acting to prevent complete return of said operating means to normal after movement in a bolt retracting direction beyond said limited movement thereof to thereby prevent relatching of said latch element and permit repeated retraction of the bolt by said operating means, and means operable in response to retraction of the bolt independently of said operating means to release the holding part and permit relatching of the latch element.

10 8. A coin controlled lock including mechanism comprising a retractable keeper engaging bolt and movable operating means therefor, said mechanism being movable in bolt retracting direction, a latch element normally allowing limited but preventing complete bolt retracting movement of said operating means and displaceable to released position, means conditioned by 15 reception of a coin to transmit movement between said mechanism and the latch element for releasing the element in response to bolt retracting movement of the mechanism, a holding part acting independently of the coin after release of the latch element to prevent relatching thereof to thereby permit repeated retraction of the bolt by said operating means, and means carried by the bolt and operable in response to retraction of the bolt independently of said operating means to release the holding part and permit relatching of the latch element.

15 9. A coin controlled lock including mechanism comprising a retractable keeper engaging bolt and movable operating means therefor, said mechanism being movable in bolt retracting direction, a latch element normally allowing limited but preventing complete bolt retracting movement of said operating means and displaceable to released position, means movable with said mechanism and conditioned by reception of a coin to transmit movement between said mechanism and the latch element for releasing the element in response to bolt retracting movement of the mechanism, a holding part acting independently of the coin after release of the latch element to prevent relatching thereof to thereby permit repeated retraction of the bolt by said operating means, and means operable in response to retraction of the bolt independently of said operating means to release the holding part and permit relatching of the latch element.

20 10. A coin controlled lock comprising a bolt movable between a normal keeper engaging position and a retracted position, a movable operator for retracting the bolt, a movable unit for trans-

mitting retracting movement from said operator to the bolt, a latch element normally allowing limited but preventing complete bolt retracting movement of said unit and displaceable to a released position, said unit including means for receiving and supporting a coin in position to transmit movement from the unit to said latch element to thereby release the latch element in response to movement of the unit in a bolt retracting direction, and a holding part acting independently of the coin to prevent complete return of said unit to normal after movement in a bolt retracting direction to thereby prevent relatching of said latch element and permit repeated retraction of the bolt by said operating means.

11. A coin controlled lock comprising a bolt movable between a normal keeper engaging position and a retracted position, a movable operator for retracting the bolt, a movable unit for transmitting retracting movement from said operator to the bolt, a latch element normally allowing limited but preventing complete bolt retracting movement of said unit and displaceable to a released position, said unit including means for receiving and supporting a coin in position to transmit movement from the unit to said latch element to thereby release the latch element in response to movement of the unit in a bolt retracting direction, a holding part acting independently of the coin to prevent complete return of said unit to normal after movement in a bolt retracting direction to thereby prevent relatching of said latch element and permit repeated retraction of the bolt by said operating means, and means operable in response to retraction of the bolt independently of said movable unit and operator to release the holding part and permit relatching of the latch element.

12. A coin controlled lock including mechanism comprising a retractable keeper engaging bolt and movable operating means therefor, said mechanism being movable in bolt retracting direction, a latch element normally allowing limited but preventing complete bolt retracting movement of said operating means and displaceable to released position, means conditioned by reception of a coin to transmit movement between said mechanism and the latch element for releasing the element in response to bolt retracting movement of the mechanism, a holding part acting independently of the coin after release of the latch element to prevent relatching thereof to thereby permit repeated retraction of the bolt by said operating means, and means for releasing said coin from said coin conditioned means upon the first return of said mechanism from retracted condition.

13. A coin controlled lock including mechanism comprising a retractable keeper engaging bolt and movable operating means therefor, said mechanism being movable to retract the bolt, a latch element normally allowing limited but preventing complete bolt retracting movement of said operating means and displaceable to a released position, means for receiving and supporting a coin in a position to transmit movement between said mechanism and said latch element to release the element in response to movement of the mechanism in a bolt retracting direction, a holding part acting to prevent complete return of said mechanism to normal after movement in a bolt retracting direction to thereby prevent relatching of said latch element and permit re-

peated retraction of the bolt by said operating means, and means for releasing said coin from said coin supporting means upon the first return of said bolt from retracted condition.

14. A coin controlled lock comprising a bolt movable between a normal keeper engaging position and a retracted position, a movable operator for retracting the bolt, a movable unit for transmitting retracting movement from said operator to the bolt, a latch element normally allowing limited but preventing complete bolt retracting movement of said unit and displaceable to a released position, said unit including two sections adapted to support a coin in position to transmit movement from the unit to said latch element and to thereby release the element in response to movement of the unit in a bolt retracting direction, said two sections being relatively movable to release the coin, a holding part acting to engage said unit and prevent its complete return to normal after movement in a bolt retracting direction to thereby prevent relatching of said latch element and permit repeated retraction of the bolt by said operator and unit, means for effecting coin releasing relative movement between said sections of the unit upon restraint of the returning movement of said unit by said holding part, and means operable in response to retraction of the bolt independently of said movable unit and operator to release the holding part and permit relatching of the latch element.

15. A coin controlled lock comprising a bolt movable between a normal keeper engaging position and a retracted position, a movable operator for retracting the bolt, a movable unit for transmitting retracting movement from said operator to the bolt, a latch element normally allowing limited but preventing complete bolt retracting movement of said unit and displaceable to a released position, said unit including two sections interconnected for retracting movement together and for limited relative movement, means carried by said sections and adapted in a first condition thereof to support a coin in position to transmit movement from the unit to said latch element to thereby release the element in response to movement of the unit in a bolt retracting direction, said unit being adapted to release the coin upon relative movement of said sections to a second relative condition, a first spring urging the sections to said first relative condition, a holding part engageable with one section of said unit to prevent complete return of the unit to normal after movement in a bolt retracting direction to thereby prevent relatching of said latch element and permit repeated retraction of the bolt by said operator and unit, a second spring acting to effect coin releasing relative movement between said sections upon restraint of the returning movement of said unit by said holding part, and means operable in response to retraction of the bolt independently of said movable unit and operator to release the holding part and permit relatching of the latch element.
